UNITED STATES PATENT OFFICE.

ROBERT O. ESHELMAN, OF HYDE PARK, PENNSYLVANIA.

PIPE WRENCH.

Application filed April 14, 1922. Serial No. 552,672.

To all whom it may concern:

Be it known that I, ROBERT O. ESHELMAN, a citizen of the United States of America, and a resident of Hyde Park, in the county 5 of Westmoreland and State of Pennsylvania, have invented a new and Improved Pipe Wrench, of which the following is a description.

My invention relates to pipe wrenches and 10 the general object of the invention is to provide a pipe wrench having novel and effective adjusting means adapting the wrench to pipes of different diameters.

The nature of the invention and its distinctive features and characteristics will 15 clearly appear as the description proceeds.

Reference is to be had to the accompanying drawings forming a part of this specification, it being understood that the 20 drawings are merely illustrative of one example of the invention.

Figure 1 is a side elevation of a wrench embodying my invention with the locking lever in release position;

25 Figure 2 is a sectional side elevation with the locking lever in locking position;

Figure 3 is a cross section on the line 3—3, Figure 2.

In carrying out my invention in accordance with the illustrated example, a movable jaw 10 is provided having a shank 11. A handle 12 constitutes at its front end a fixed jaw. Both jaws are toothed, the teeth on the fixed jaw being in a plane inclined 30 to lie oblique to the axis of the handle 12, the row of teeth sloping forwardly or toward the movable jaw 10 in practice so that the space between the jaws is slightly flaring from the inner ends of the jaws outwardly.

40 A strap 13 of U-shape is disposed at opposite sides of the fixed jaw and affords a space at the back edge of the fixed jaw to accommodate the shank 11 to permit of a relative sliding movement of said shank and handle 12 with its fixed jaw. The strap 13 is secured at one end to the fixed 45 jaw by a transverse rivet 14 or equivalent means to permit pivotal movement of said strap, while rearward of the pivot 14; a

50 transverse pin or pivot 15 extends through slots 16 in the sides of the strap 13 and through the fixed jaw, the slot permitting a limited movement of the handle 12 to and from the shank 11 of the movable jaw 10 with the pin 14 as an axis. Along that edge 55 of the shank 11 adjacent to the handle 12

rack teeth 17 are provided on said shank and a pinion 18 adapted to mesh with said rack is turnably mounted on the pin 15 or an equivalent pin, said pinion being disposed in 60 a slot 12^a in the fixed jaw. The rocking of the handle 12 about the pivot 14 serves to engage or disengage the pinion 18 and rack teeth 17. With the pinion disengaged the shank 11 may be freely slid forward or back 65 along the handle 12.

A lever 19 is secured at its front end by a pivot 20 in the slot 12^a of handle 12 and said lever has a tooth 21 or a plurality of teeth to engage between teeth of the pinion 18. The 70 lever 19 when swung outwardly permits free relative sliding movement of the handle 12 and shank 11 and when swung inwardly to the position in Figure 2 and the pinion 18 engaged with the rack teeth 17, said pinion 75 cannot turn because of being held by the teeth 21 and thus the wrench is locked in adjusted position.

I would state in conclusion that while the illustrated example constitutes a practical 80 embodiment of my invention, I do not limit myself strictly to the exact details herein illustrated, since, manifestly, the same can be considerably varied without departure 85 from the spirit of the invention as defined in the appended claims.

Having thus described my invention, I claim:

1. A wrench comprising a movable jaw having a shank, a separate handle constituting at its front end a fixed jaw, a U-shaped strap secured to the opposite sides of the fixed jaw and pivotally connected at its one end to said fixed jaw, and connected to the fixed jaw at a point distant from said pivot 95 by a slot and pin connection, rack teeth on said shank, a pinion on the fixed jaw, and means to lock said pinion against rotation.

2. A wrench comprising a movable jaw having a shank, a separate handle constituting at its front end a fixed jaw, a U-shaped strap secured to the opposite sides of the fixed jaw and pivotally connected at its one end to said fixed jaw, and connected to the fixed jaw at a point distant from said pivot 100 by a slot and pin connection, rack teeth on said shank, a pinion on the fixed jaw, and a lever pivoted at its front end to the fixed jaw to swing laterally outward or inward, and means on said lever to engage said pinion and lock said member against movement.

ROBERT O. ESHELMAN.
